UNITED STATES PATENT OFFICE.

DAVID C. DEMAREST, OF ANGELS, CALIFORNIA.

HYDRAULIC VALVE MECHANISM.

SPECIFICATION forming part of Letters Patent No. 665,192, dated January 1, 1901.

Application filed March 28, 1900. Serial No. 10,573. (No model.)

To all whom it may concern:

Be it known that I, DAVID C. DEMAREST, a citizen of the United States, residing at Angels, Calaveras county, State of California, 5 have invented certain new and useful Improvements in Hydraulic Valve Mechanism; and I do hereby declare the following to be a full, clear, and exact description of said invention, such as will enable others skilled in 10 the art to which it most nearly appertains to make, use, and practice the same.

The object of my invention is to provide a controlling valve mechanism for operating the gates or valves of two or more hydraulic 15 nozzles, so that the movement of a single lever will serve to open or close all or one or more of the nozzle gates or valves, as required.

The particular use to which my controlling 20 valve mechanism is applied is for regulating the delivery of streams of water under pressure through two or more hydraulic nozzles upon the buckets of a water-wheel, so that one or more streams can be delivered upon the wheel, according to the power required, 25 and I have therefore represented it in that connection in this application.

It consists, primarily, in providing each of the several nozzles with an independent valve or gate which can be opened or closed by hydrostatic pressure applied through the medium of a piston moving in a cylinder, and, secondly, in independently connecting each of these cylinders with a common pressure-cylinder in which a sliding valve is moved by 35 means of a lever in such manner that the movement of the sliding valve in the common cylinder supplies water to and exhausts it from the nozzle-cylinders, so as to move the pistons in the nozzle-cylinders and operate 40 the nozzle-valves either simultaneously or consecutively, according to the position of the governing or valve piston, and, thirdly, in supplying water-pressure to the common cylinder from the main pressure-pipe that supplies 45 water to the nozzles in order to supply water to operate said valves, all as herein-after more fully described.

Referring to the accompanying drawings, Figure 1 is a perspective showing my valve 50 controlling and regulating mechanism in connection with multiple nozzles for delivering streams of water against the buckets of a

water-wheel. Fig. 2 is a longitudinal vertical section of the hydraulic valve-cylinder, showing the piston and its connecting ports. Fig. 55 3 is a vertical transverse section of the same; and Fig. 4 is a sectional view of one of the nozzle-valve cylinders and its valve, showing its port connection with the main-valve cylinder.

60

Let A represent a main pipe, which conducts water under pressure to two or more nozzles B B' B² for the purpose of delivering the water against the buckets of a water-wheel. (Shown in dotted lines at Fig. 1.) 65 Each nozzle has connected with it a piston-operated valve, which in this instance is represented as a sliding cut-off valve or gate, which moves across the nozzle-orifice in a chamber inside the casing, (marked C C' C².) 70 Connected with each one of these valve-chambers is a short cylinder D D' D². In each one of these cylinders a piston E moves and is connected by a rod passing through the intermediate casting F F' F² with the valve-or 75 gate, so that as the piston is moved in its cylinder the cut-off valve or gate is opened or closed, according to the direction in which the piston moves. At a convenient distance from these nozzles and their attached cylinders and 80 valves I mount a long cylinder G on a suitable platform H. Inside of this cylinder a long spool-shaped piston G' is placed, and a piston or valve rod 3 extends from the piston G' through one end of the cylinder to a hand-lever 5 within reach of the engineer. The long spool-shaped piston G' consists of two heads J J', connected by a reduced portion k, so that the space surrounding the reduced portion k between the two heads forms a 85 chamber for the purpose hereinafter described. The heads J J' of this piston are each made to fit tight in the cylinder, and for this purpose I prefer to surround them with the ordinary cup-leather used for packing 90 pump-pistons, so that they will not only form a close packing, but will permit the piston to move easily in the cylinder. The valve-rod 3, which passes through the closed head of the cylinder G and is connected at its outer 100 end with lever 5, has its opposite end connected with the piston inside the cylinder, so that the piston can be moved back or forth inside the cylinder by means of the lever.

95

100

- A pipe 6 leads from the main pipe A and connects with the cylinder G at about its middle. I prefer to connect it with the bottom of the cylinder G; but this is not material.
- 5 On each side of this supply-pipe 6 are three ports (marked, respectively, $e e' e^2$ and $i i' i^2$) leading into the chamber. The ports $e e' e^2$ are connected, respectively, with the outer ends of the cylinders D D' D² by pipes, (marked 10 7,) while the ports $i i' i^2$, on the opposite side of pipe 6 are connected with the opposite or inner ends of the cylinders D D' D² by pipes, (marked 8.) The distance between the heads J J' of the piston is sufficient to allow 15 the supply-port of pipe 6 and all the ports which connect with the nozzle-chambers on one side of pipe 6 to be covered by the space between the heads, so that this space will constitute a movable pressure-chamber, which 20 can be shifted in the cylinder G to cover or uncover any one or more of the side ports connected with pipes $e e' e^2$ or $i i' i^2$. Pipe 6 supplies water from the main to the movable chamber in the cylinder, so that it will have 25 the same pressure that there is in the main pipe, and the pipes $e e' e^2$ and $i i' i^2$ supply water from this pressure-chamber to operate 30 the nozzle-pistons and their gates in the following manner: In the position in which the piston and its chamber are represented in Fig. 2 of the drawings the pipe 6 and also all 35 the ports represented by the pipes $e e' e^2$ on one side of pipe 6 are connected with the chamber, so that the water-pressure in the 40 chamber is transmitted through the pipes $e e' e^2$ to the outer ends of all three of the nozzle-cylinders D D' D², so that the pistons of all three of the cylinders are forced toward 45 their nozzles and the gates are thereby closed. The other three pipes $i i' i^2$, which connect the opposite ends of the nozzle-cylinders D D' D² with the main cylinder G, have their 50 ports or points of entry into cylinder G uncovered by the piston, so that in this position they connect with the open cylinder. The cylinder G may be open at both ends, so as to waste the water discharged by the spool-shaped piston G' on either side; but I prefer to close the end through which the piston-rod 55 passes and to connect that end of the cylinder with the opposite or open end by a side passage L, which connects at one end with the cylinder near the closed end and with the opposite end near the open waste end, so that any water-pressure which may have been included 60 within the pipes $i i' i^2$, leading from the opposite ends of the nozzle-cylinders D D' D², is relieved and the water is discharged into the cylinder and thence out through the side passage L and through the open end of the cylinder to the place of waste.
- If the lever 5 be moved so as to draw the piston toward the closed end of cylinder G, the head J of the piston uncovers the ports 65 e , e' , and e^2 successively, so as to connect them directly through their connecting-pipes with the waste-opening of the cylinder, and

simultaneously as each port $e e' e^2$ is passed by the head J the opposite head J' of the piston passes over and covers one of the ports $i i' i^2$, so that the water-pressure is transferred to the opposite ends of cylinders D D' D², while the water from the relieved ends of the cylinders D D' D² is released and forced by the movement of the nozzle-piston E out through the pipes $e e' e^2$ and through the waste end of cylinder G. This transfers the pressure from the outer to the inner ends of cylinders D D' D², so that the pistons in cylinder D D' D² are moved outward and the nozzle-gates are opened successively.

It is readily apparent that the piston in chamber G can be moved by lever 5 to any intermediate point, so as to transfer the water-pressure from the pressure-chamber of the piston to the opposite end of one or more of the three (more or less) nozzle-cylinders, and for the purpose of regulating the movement I employ a sector-rack 8 for the lever to move against and provide stop-holes 9, in which a spring-pin on the lever enters as the lever moves, so as to determine the proper point to set the valve for any particular nozzle. Both ends of the cylinder G are thus always open to the waste or exhaust pipe. The front end of the cylinder might have a waste-pipe tapped into it, so as to discharge independently of the back end; but I prefer to discharge both ends through the back pipe by employing the cored side passage.

In the construction of the cylinder G, I shall usually employ a removable brass bushing 11 to form the smooth bore of the cylinder. Holes or ports are made in the bushing opposite the annular channels to admit the water 105 into the pressure-chamber of the spool-shaped valve, and it can be readily removed and replaced when desired.

In order to allow the water from pipe 6 to enter freely all around the pressure-chamber 110 of the piston, I provide annular grooves 10 in the outer casing of cylinder G, which extend entirely around the casing, and these grooves are arranged opposite each port, so that the movement of the piston-heads cut 115 them off or introduces them into the chamber simultaneously with the ports.

Where I have used the term "ports" I have intended to refer to mere openings, as it is apparent that the pipes or tubes may be 120 screwed into proper threaded holes in the casings of the cylinder and accomplish the same purpose; but for the purpose of representing a fixed mechanism I have shown a heavy base for the main cylinder with fixed ports 125 in the base, and the pipes are connected with these ports.

While I have shown sliding valves for cutting off the stream to the nozzle, it is apparent that a rotary or other valve could be used 130 and the connection with the operating nozzle-pistons modified accordingly, which can be done by any ordinary mechanic.

It will be observed that the double-headed

or spool-shaped piston which moves in the cylinder G has no external pressure upon it. The pressure-chamber is inside the valve and the pressure is the same in all directions, so that it will move freely in the cylinder. By this arrangement an engineer is able to control and operate two or more hydraulic nozzles at any distance from the operating mechanism by means of a single lever. He can open all the nozzle-gates at once by moving lever 5 entirely across the rack, or he can stop it at the first notch, so as to open the gate of one nozzle, or he can open two or more, according to the number of nozzles connected with the apparatus, or he can open one nozzle full and any fractional part of the second nozzles, or two nozzles full and any fractional part of the third nozzle.

Having thus described my invention, what I claim, and desire to secure by Letters Patent, is—

1. A controller for the gates of hydraulic nozzles consisting of a hydraulic cylinder connected at or near its middle with a source of water-pressure; a plurality of ports on each side of said supply-port; a spool-shaped valve or piston adapted to cover the supply-port and one-half the number of side ports; a plurality of nozzles equal to the number of ports on one side of the supply-port; a supplemental cylinder connected with each nozzle in which is contained a piston that operates to open and close the valve that admits water to the nozzle; a port on each side of the piston in the nozzle-cylinder, the port on the outer end of each nozzle-cylinder connecting with the controlling-cylinder on one side of its supply-port while the port on the opposite side of the piston connects with the controlling-cylinder on the opposite side of the supply-port and means for moving the spool-shaped piston so as to cover or uncover any one of the side ports in the controller-cylinder substantially as described.

2. A controller for opening and closing the gates or valves of two or more hydraulic nozzles, consisting of a separate cylinder connected with each hydraulic nozzle; a piston moving in each of said cylinders and connected with the valve or gate that closes the nozzle-orifice; a separate horizontal cylinder having a waste-passage at both ends; a movable pressure-chamber contained in said separate horizontal cylinder and adapted to move horizontally therein; means for supplying a fluid-pressure to said movable pressure-chamber; ports in one end of the horizontal cylinder connecting with one end of the nozzle-gate-operating cylinders and ports in the opposite end of the horizontal cylinder connecting with the opposite ends of the nozzle-gate-operating cylinders, and means for moving the pressure-chamber in the horizontal cylinder so as to simultaneously cover all the ports leading to one end of the nozzle-cylinders and uncover all the ports leading to the opposite end of the nozzle-cylinder or to cover one or more of the ports on one end and uncover one or more ports at the opposite and corresponding end, substantially as described.

3. In a controller for operating the gates of two or more hydraulic nozzles, a horizontal cylinder; a port at or about the middle of said cylinder connecting it with a source of water-pressure; ports on each side of said supply-port connecting with the opposite ends of independent cylinders; a spool-shaped piston adapted to cover the supply-port and one-half the number of ports leading to the independent cylinders, and means for moving said spool-shaped piston longitudinally in the cylinder, substantially as described.

In witness whereof I have hereunto set my hand this 20th day of December, A. D. 1899.

DAVID C. DEMAREST.
